CAN CONVEYER

John E. Schmidt, Chicago, Ill., assignor to Continental Can Company, Inc., New York, N. Y., a corporation of New York

Application August 10, 1934, Serial No. 739,332

5 Claims. (Cl. 193—31)

This invention relates to new and useful improvements in control mechanism for article conveyers or feeders and the like, wherein the articles being conveyed or fed along a path of delivery are directed into dividing ways of passage according to some circumstance or condition.

An object of the invention is to provide an automatically operable mechanism controlled by the articles themselves, for diverting the same from a normal path of movement to another when said normal path becomes overloaded with the articles, or when some other condition planned for occurs, and to restore the articles to the original normal path of movement when the overloading is relieved therefrom, or such other condition has passed.

Another object is to provide in such a mechanism, a novel actuating device for moving a member to and from alternative positions closing and opening, or opening and closing a way of passage for the articles along the conveyer.

A further object is to provide such a mechanism and incorporate device which will be applicable for the stated or analogous purpose to various article conveying or feeding apparatuses, such as elevators and cable or gravity runways, where a governing of plural or dividing ways of passage is desired, so as to eliminate the need of many different kinds of mechanisms for the different requirements of each particular installation.

These and other objects in addition to the general concept and advantages of the invention will be in part rendered obvious and in part more fully disclosed to complete understanding by the following description with reference to the attached drawings, illustrating one practicable embodiment of the same applied to an ordinary type of can conveyer used to pass such articles from one processing machine to another.

In said drawings:

Figure 1 is a side view of a conveyer showing the applied control mechanism in position of operation directing the articles along the normal path of movement;

Fig. 2 is a similar view showing the mechanism in position of directing the articles along a different path of movement;

Fig. 3 is a side view of a different or modified form of conveyer having the mechanism operatively applied;

Fig. 4 is an enlarged longitudinal sectional view of the member-actuating device part of the mechanism;

Fig. 4a is a fragmentary view of said device

showing one of its parts in a different operative position;

Fig. 5 is an enlarged bottom view of the member-actuating device part of the mechanism;

Fig. 6 is a similarly enlarged side view of a portion of said device; and

Fig. 7 is a sectional view on the line 1—7 of Fig. 6, looking in the direction of the arrows.

It may facilitate understanding to state that the invention is directed to an automatic control mechanism for an article conveyer having one or more dividing paths or ways along which the articles can be passed in their movement so as to separate, distribute or assort them, which mechanism is so constructed and so applied to the conveyer as to selectively open and close the respective paths or ways thereof to passage of the articles, and is controlled in such operation by the articles themselves. This mechanism may be applied to any type of conveyer or feeder so as to function as desired according to any circumstance or condition for which it is adapted, as will be later explained, but is designed more especially for different forms of can conveyers so as to operate according to circumstances of load in supply delivery to a machine or point, the purpose being to thereby prevent a congestion of the cans in the conveyer way by oversupply of the same which would be likely to cause a jam.

In the illustrative embodiment, an article conveyer is represented by the section of runway or trackway 8. Figs. 1 and 2 show this incline in a gravity type of conveyer and Fig. 3 shows it disposed vertically in an elevator type of conveyer.

In the later case, a driving cable or belt 9 is used to move the articles along their path of travel. The articles as shown are cylindrical, and the belt bearing against the cylindrical article will cause it to bear against the guideway, and as the belt travels upward, it will rotate the cylindrical articles, and this will cause the same to travel up the guideway. This is a common form of means for conveying articles such as cans upward along runways.

This conveyer has a branch formed by the gravity runway 10 extending therefrom, which together with the continuing portion of the conveyer provides dividing ways along which the conveyed articles may be directed. Said branch in this instance delivers to a machine (not shown) which is to be supplied with the articles for operation in a manufacturing process. The continuing portion of the conveyer designated for reference by 8a in Figs. 1 and 2, and formed by the lateral passage 8b in Fig. 3, extends onward

toward other machines of the manufacturing line, or to some other point of intended delivery.

The articles, in this instance comprising partially made or finished cans 11, are directed along 5 one or the other of the dividing conveyer ways by automatically operable mechanism opening and closing said ways alternately as the branch runway 10 becomes overloaded and relieved of over-load in delivery to the machine; the purpose being to prevent a jam in said branch and maintain a regular supply of the articles therein to said machine.

Said automatically operable mechanism, which is controlled by the articles themselves, includes 15 a guide member 12 swung normally across the conveyer to divert the articles into the branch runway, and a sliding plate member 13 normally retracted from over the entrance of said runway to permit the articles to pass thereinto. (See 20 Figs. 1 and 3.) These two members are simultaneously operated to swing and slide respectively to opposite position and relation, with the guide member 12 retracted from across the conveyer and the plate-member 13 advanced over the 25 branch runway entrance, so as to open the way for the articles along the continuing portion of the conveyer and close the way to the branch passage (see Figs. 2 and 3). Support for the guide member 12 is desirably provided by a bracket 14 30 on the conveyer, to which it is shown pivoted at 15. Support for the plate member 13 is advantageously provided by a rest plate 16 shown fastened to the conveyer by bolts or clamps 17.

The aforesaid sliding plate member 13 is moved 35 to its positions forward and back by an actuating device composing part of the automatic control mechanism. This device, shown in detail by Figs. 4 to 7, includes a rod 18 to one end of which said member is connected, as by a lug 13a having a pin fastening therewith. The other end of said rod extends into a cylinder 19 and carries a piston 20 working therein, which consists in this instance of a leather cup having metal follower heads at opposite sides screwed onto the 40 rod. A block 21 in the end of the cylinder, through which the rod extends thereinto, provides a guide for the rod as well as a closure for the cylinder. This block is advantageously secured in place by screw-bolts 22.

Said cylinder 19 is supported by bracket members 23 on the conveyer, with its longitudinal axis in a common plane with the axis of the slide plate movement. On the end of the cylinder opposite the rod entry thereinto is attached a valve body 55 24, closing it at that end. Connected between this valve body and the outer end of said rod at opposite sides of the cylinder are springs 25, serving to draw and hold the rod normally retracted, with the piston 20 at its inward limit of movement and the slide plate 13 in the latter's retracted position. Accommodation for the connection of these springs is advantageously provided by studs 26 on the sides of the valve body and a cross-bar 27 on the rod (see Fig. 5), the latter being affixed preferably by an adjustable clamp 27a for varying the tension of the springs as required.

The valve body 24 has a passage 28 therein opening into the cylinder for admission of a fluid 70 to impel the rod by action on its piston, so as to advance the slide plate 13 to closing position. This fluid passage, of angular course in this instance, communicates with an introductory pipe 29 connected to said valve body from a source 75 (not shown) of fluid supply, such as compressed

air. Extending thereinto from the side of the valve body (see Fig. 7) is an adjusting screw 30 for regulating the volume flow of the fluid there-through, so as to govern the speed of its impelling action upon the piston. Across said passage 5 within the valve body, a sliding valve 31 moves in a guide slot 32. Said valve has an inlet trans-verse port 33 registering at both sides with the passage 28 in one position of its operation (see Fig. 4a) and an exhaust L-shaped port 34 regis-10 tering with said passage only at one—the cylinder-side in the other position of its operation (see Fig. 4), the last-named port opening through the valve end into its guide slot which in turn opens to the atmosphere, or to a conductor pipe 15 if it is desired to reclaim the fluid used. Thus the valve in its alternate positions is adapted to admit the fuel to the cylinder and to exhaust the same therefrom.

The valve just described has its outer end at-20 tached to a lever 35, in this instance intermediate the ends of the latter, with allowance for dif-ferential movements as by a pin and slot connec-tion indicated at 36. This lever is pivoted at one end to a bracket 37 fastened to the valve body 24, 25 with its portion between the pivot and said connec-tion with the valve preferably constituting the shorter arm thereof. Its other long-arm end is attached by pin and slot connection 38 to a solenoid plunger 39, moving in the core of an 30 electro-magnetic coil 40 which is secured within a suitable housing to the valve body.

Said lever swings inward and outward in move-ment of the valve 31 as indicated by the full and dotted lines in Fig. 4. Its outward swing is 35 limited by a retainer bracket 41 to the position at which the valve brings its exhaust port 34 into register with a part of the passage 28 as shown in Fig. 4, and a spring 42 around the valve, between said lever and a shoulder in the valve body, 40 presses it normally to said position. Its inward swing is limited by a shoulder of the plunger 39 to the position at which the valve brings its inlet port 33 into register with said passage 28 as shown in Fig. 4a, and is occasioned by the ener-gization of the coil 40 drawing said plunger in-45 ward. Thus when the valve is moved to its in-ward position, the compressed air or other fluid will be admitted to the cylinder to drive the piston rod outward; and when the valve is moved to its 50 outward position, the piston rod will be retracted by its springs and expel the air from the cylinder.

The aforesaid guide member 12 is swung to its positions forward and back by a similar actuating device, or, as in this instance, simply by an 55 electro-magnetic device 43, also comprising part of the automatic control mechanism (see Figs. 1 to 3). This last named device, shown fastened to the bracket 14 on the conveyer, comprises a coil (not shown) like the coil 40 of the first-named device, in the core of which a solenoid plunger 44 moves. The guide member is con-nected to this plunger by a link 45.

The described actuating devices are connected in an electric circuit, represented by the con-60 ductor wires 46 and 47 connecting with a power source (see Figs. 1 and 2), for energizing the magnetic coils (40 and like element of 43) and this circuit is governed by a make and break de-70 vice controlled by the conveyed articles them-selves. Said governing device advantageously comprises a mercury switch 48 applied at the desired point of control, which is located in this instance on the branch runway 10 a short dis-tance from its juncture with the main runway of 75

the conveyer. This switch is mounted on a tilting axis adjacent a controlling member acted upon by the articles on said branch runway. The controlling member shown comprises a pivoted plate 49 in the bottom of the runway, having connection with a balancing arm 50 on the axis of the switch, by which it is held normally out of flush with such bottom, that is, with its free end raised slightly above the runway surface (see Fig. 1). In this position the mercury switch breaks and holds the circuit open. However, when said plate is depressed or swung flush with the runway bottom by a pressure or load, thereby tilting its balancing arm on the switch axis, the switch will be correspondingly tilted so as to close the circuit (see Fig. 2).

The operation of the mechanism will probably be apparent from the foregoing description. In the arrangement shown, it causes the articles or cans advanced along the conveyer to be directed normally, by the guide member 12, into the branch runway 10 in supply to the machine which is to operate upon them. While thus functioning, the parts are in the positions illustrated in Figs. 1, 3 and 4. Passing one after another over the controlling member 49 in the runway surface, the articles ordinarily have no effect upon said member, due to insufficient weight. However, when, as the result of supply faster than the machine receives them, the articles accumulate back to this member in overload of the runway with several resting upon the member, the combined weight thereof depresses it to operate the switch 48 and close the electric circuit.

With the closing of the circuit, the electromagnet coils 40 and 43 are simultaneously energized so as to draw their respective plungers inward. The drawing of plunger 39 swings the lever 35 in actuation of the valve 31 to its fluid admission position, whereupon the fluid under compression from its supply is released to impel the rod 18 from its cylinder and advance the slide plate 13 over the branch runway entrance. The drawing of plunger 44 swings the guide member 12 from across the conveyer path. These movements are rapidly performed so as to close the branch runway and open the way to article movement along the continuing part 8^a (or 8^b) of the conveyer. While functioning in the latter manner, the parts of the mechanism are in the positions illustrated in Figs. 2, 4a and the dotted line indications of Figs. 3 and 4.

When the weight upon the controlling member 49 is relieved by the articles moving off of the same so that the switch 48 moves to again open the circuit, the coils 40 and 43 will be deenergized and the parts return to normal position, the rod 18 being retracted by the recoil springs 25 with an exhausting of the fluid from its cylinder through the exhaust port of valve 31, and the guide member 12 being readvanced across the conveyer by gravity or a suitable spring.

Thus the mechanism operates automatically, under control of the articles themselves, to direct the articles into one or the other of the dividing conveyer ways according to a condition or circumstance of their supply.

It will be appreciated that this mechanism may be applied to various types of conveyers so as to operate in the same or in different ways and for like or different purposes. Obviously, it is not limited to conveyers having only two dividing ways, since mere addition or duplication of actuating parts is necessary to control any number

of passways as desired. In accommodation to different installations the control by the articles may be placed at any point on the conveyer other than that shown, and may be made to depend upon some other condition or circumstance than weight, as for example, size or form. Numerous possibilities of use of the mechanism exist, apart from the particular object of its design, as for instance in the distribution, assortment or grading of manufactures, produce or material. The advantages of the invention will be recognized.

Inasmuch as various changes to suit conditions and requirements can be made in the form, construction and arrangement, with different combinations and subcombinations of parts, without departing from the spirit of the invention, it is not intended to limit the same by the appended claims to the specific embodiment shown and above described.

What I claim as my invention and desire to secure by Letters Patent of the United States is:

1. An automatic control mechanism for article conveyers, comprising in combination with a conveyer having a dividing way of passage, a movable member normally directing the articles from the main into the dividing way, a second movable member normally opening said way to the articles, and means controlled by the articles themselves for moving said members to position for opening the main conveyer way and closing the dividing way when said dividing way becomes overloaded with the articles thereon.

2. An automatic control mechanism for article conveyers, comprising in combination with a conveyer having a dividing way of passage, a movable member normally directing the articles from the main into the dividing way, a second movable member normally opening said way to the articles, and means controlled by the articles themselves for moving said members to positions for opening the main conveyer way and closing the dividing way when said dividing way becomes overloaded with the articles and means for automatically restoring said members to their original position when the overloading is relieved.

3. An automatic control mechanism for article conveyers, comprising in combination with a conveyer having a dividing way of passage, a member movable across the main path of the conveyer to direct the articles into the dividing way, a second member movable across the entrance of the dividing way to close the same, means for moving the first-named member from across the conveyer path, means for moving the second member over the dividing way entrance, and means controlled by the articles themselves for simultaneously operating both of said moving means when the dividing way of passage becomes overloaded with the articles passed thereto.

4. An automatic control mechanism for article conveyers, comprising in combination with a conveyer having a dividing way of passage, a member movable across the main path of the conveyer to normally direct the articles into the dividing way, a second member movable across the entrance of the dividing way to close the same left normally open, actuating means for moving the first-named member from across the conveyer path, actuating means for moving the second-named member over the dividing way entrance, and means controlled by the articles themselves including a switch in an electric circuit for operating said actuating means so as to move said members to position closing the divid-

ing way and opening the main way of the conveyer when said dividing way becomes overloaded with the articles and means for automatically returning said members to their original position when said overloading is relieved.

5. An automatic control mechanism for article conveyers, comprising in combination with a conveyer having a dividing way of passage, a swinging member, means for normally position-
10 ing said member across the main path of the conveyer so as to direct the articles into the dividing way, a slidable member, means for normally re-
tracting said slidable member from over the en-
trance of said dividing way, means including an
15 electro-magnet for swinging the first-named

member out of normal position opening the main path, means including an electro-magnet for sliding the second-named member over the dividing way entrance, an electric circuit in which said electro-magnets are connected, and means on the 5 dividing way of passage including a switch controlled by the articles themselves for closing said circuit to energize the magnets into operation of the first-named means when said dividing way becomes overloaded with the articles and to deenergize the same when the overloading is relieved to permit said members to be moved to normal positions so as to again direct the articles into the dividing way.

JOHN E. SCHMIDT. 15
